UNITED STATES PATENT OFFICE.

MAURICE KAUNITZ AND SAMUEL LANZET, OF NEW YORK, N. Y.

STEAM DRIER.

Application filed August 11, 1925. Serial No. 49,510.

To all whom it may concern:

Be it known that we, MAURICE KAUNITZ and SAMUEL LANZET, citizens of the United States, residing at New York, in the county of New York and State of New York, have invented certain new and useful Improvements in Steam Driers, of which the following is a specification.

The main object of this invention is to provide an improved type of construction for a drying kiln having special features adapted for concentrating the heat in an area above a conveyor belt upon which the material to be dried is approximately thru the entire length of the kiln, entering at one end with its surfaces in treated condition, and existing at the opposite end as a completely dried product.

Another object is to provide a drying kiln having a novel arrangement of steam coils for generating the heat used in the kiln. This drying kiln is designed particularly for the purpose of drying a lithographic paper or the like upon which a glazing coat such as shellac or varnish has been applied and is further adapted to completely dry the varnish on the material in its passage thru the drying kiln on a conveyor.

The above and other objects will become apparent in the description below, in which characters of reference refer to like-named parts in the drawing.

Referring briefly to the drawing, Figure 1 is a side elevational view of the drying kiln, showing a portion thereof broken away to illustrate the interior design.

Figure 2 is a top plan view of Figure 1, with various portions thereof broken away to disclose the interior.

Referring in detail to the drawing, the numeral 10 indicates the roof of a relatively long compartment, the shortest possible length for arriving at good results being approximately 30 feet. The roof of the kiln is joined at its longitudinal edges by sides 11 and 12 and has a bottom 13 which provides a relatively long hollow chamber 14 in which the entire drying apparatus is housed. The drying kiln is open at both ends and is supported upon stanchions consisting of angle irons 15 in order to raise the kiln to a convenient position for its use. At one end a skeleton structure consisting of a post 16 removed some distance from the end stanchions 15 is connected therewith by inclined angle irons 17 which

form a platform on which bearing lugs 18 are mounted. These bearing lugs support a shaft 19 on which a roller 20 is mounted. At one open end of the drying kiln, a roller 21 is mounted on a shaft journaled in the framework of the kiln and an endless conveyor belt 22 is trained about these rollers 20 and 21, passing longitudinally thru the drying kiln which receives the material from the feeding platform provided by the structure members 16 and 17. Where the conveyor belt 22 enters the drying kiln, adjacent the feeding platform, a pair of rollers 23 and 24 are mounted in the framework of the kiln, one above the other so that the upper roller 23 supports the upper surface of the conveyor belt 22 while the lower surface of the conveyor belt rides between both rollers 23 and 24 and is supported by the latter. This construction is necessary in order to permit the conveyor belt to enter the drying kiln at an inclined plane and then diverge to the horizontal.

Near the delivery end of the drying kiln and beside the latter, a boiler 25 or other means of generating steam is mounted on a base 26. A steam delivery pipe 27 extends from the boiler toward a position intermediate the length of the drying kiln and enters into the chamber 14 of the drying kiln thru pipes 28. Within the kiln below the conveyor belt 22, two sets of delivery manifolds 29 are mounted in a suitable manner and are connected to the pipes 28. From these delivery manifolds 29, a plurality of heat radiating tubes 30 extend parallel at an inclined plane toward the outer ends of the drying kiln and terminate in return manifolds which communicate with each other thru a steam return pipe 33, which has an outlet pipe 34 connected thereto, the latter leading directly to the boiler 25.

The material with which this drying kiln is to be used is paper or the like, coated with varnish or shellac which must be quickly dried. These sheets of material after being coated with a given substance are laid upon the conveyor belt 22 on the feeding platform comprised of the members 17 and 16. This conveyor belt is actuated by a source of power not shown on the drawing and slowly passes into the drying kiln, extending thru the entire length of the kiln and conveying the material thereon thru the kiln to the opposite end of said kiln where it is de-

livered in dried condition. The heat radiating from the steam pipes 30 passes upwardly, heats the conveyor belt, and circulates into the chamber between the upper 5 surface of the conveyor belt and the roof 10 of the drying kiln, and in this manner, treats both the upper and lower surface of the material being dried. The pipes 30 are inclined toward the outer ends of the drying 15 kiln in order to serve as drains for the condensed vapor in the coil system, which vapor enters the return pipe 33 and is delivered to the boiler 25.

We claim:—

- 15 1. A drying kiln comprising a longitudinal body open at both ends, coils in said kiln extending from the center to the open ends of the kiln, and a conveyor passing thru said kiln.
- 20 2. A drying kiln comprising a longitudinal body open at both ends, rollers at said open ends of the body, a platform formed at one end of said body supporting a roller thereon, a conveyor belt passing over the platform entirely thru the drying kiln, a 45 boiler exterior of said kiln, coils in said boiler comprising manifolds mutually spaced apart, pipes connecting said manifolds, said boiler communicating thru pipes with adjacent manifolds, and a return pipe connecting the opposing manifolds with the boiler.
- 25 3. A drying kiln comprising a longitudinal body open at both ends, rollers at said kiln connected to said boiler.

open ends of the body, a platform formed 30 at one end of said body supporting a roller thereon, a conveyor belt passing over the platform entirely thru the drying kiln, a boiler exterior of said kiln in said boiler comprising manifolds mutually spaced apart, 35 pipes connecting said manifolds, said boiler communicating thru pipes with adjacent manifolds, and a return pipe connecting the opposing manifolds with the boiler.

4. A drying kiln comprising a longitudinal body open at both ends, rollers at said open ends of the body, a platform formed at one end of said body supporting a roller thereon, a conveyor belt passing over the platform entirely thru the drying kiln, a 45 boiler exterior of said kiln, coils in said boiler comprising manifolds mutually spaced apart, pipes connecting said manifolds, said boiler communicating thru pipes with adjacent manifolds, a return pipe connecting 50 the opposing manifolds with the boiler, said coils being inclined from the center to a lower level outwardly toward the open ends of the kiln to drain the return pipes.

In testimony whereof we affix our signatures.

MAURICE KAUNITZ.
SAMUEL LANZET.
